UNITED STATES PATENT OFFICE.

THOMAS C. COOPER, OF CHICAGO, ILLINOIS.

LOCK.

Application filed March 1, 1923. Serial No. 621,997.

To all whom it may concern:

Be it known that I, THOMAS C. COOPER, a citizen of the United States, residing at Chicago, in the county of Cook and State 5 of Illinois, have invented certain new and useful Improvements in Locks, of which the following is a specification.

This invention relates to improvements in locks, and more particularly to tire locks, 10 although, as will be apparent from the following description, the improvements are not limited to such use, but, on the contrary, are of much broader adaptation and capable of use in many other connections.

15 One object of the invention is to provide a lock of the class described which shall be simple in construction and operation and economical to manufacture, and one which at the same time shall possess the 20 desired ruggedness and security, so essential in locks of this character.

Other objects and advantages will appear from the following description, taken in connection with the accompanying drawings, 25 wherein one form of the invention is illustrated.

In the drawings—

Figure 1 is a front elevation of a lock constructed in accordance with the present 30 invention;

Fig. 2 is an enlarged sectional view, taken on the line 2—2 of Fig. 1;

Fig. 3 is a sectional view similar to that shown in Fig. 1, but showing the locking element released;

Fig. 4 is a sectional view, taken on the line 4—4 of Fig. 2;

Fig. 5 is a sectional view, taken on the line 5—5 of Fig. 2;

40 Fig. 6 is an enlarged sectional view illustrating the construction of the cable or locking band; and

Fig. 7 is a sectional view, taken through a cable or band of slightly modified construction.

Referring more in detail to the drawings, 45 9 designates the lock casing, the same being provided with a plurality of openings 10 and 11 extending therethrough from top to bottom, and said casing having formed therein, intermediate said openings and extending at right angles thereto, a well 12 or the like. The casing is, preferably, in the form of an integral casting of some special 55 alloy metal.

Slidably mounted in the well 12 is the locking element 13, in the form of a substantially cylindrical plug-like member, of a diameter to fit said well snugly. The locking element is headed at its outer end, as 60 shown at 14, which head serves to limit the inward travel of the locking member by engagement with the countersunk shoulder 9^a of the casing. The outward travel of said element is limited by the head 15 of guide 65 rods 16, which extend through said element and are anchored at their inner ends in the adjacent wall of the casing. Coil springs 17 surround these rods and are interposed between the adjacent wall of the casing and 70 the inner end of the plug-like locking element 13, which springs normally tend to force said element outwardly, as shown in Fig. 3 of the drawings. The heads 15 of the guide rods operate in suitable sockets 18 75 formed in the outer face of the locking element, the head 14 of said element limiting the inward movement thereof, as previously described, and the heads 15 of the guide rods 16 limiting the outward movement thereof 80 by engagement with the shoulders at the bottom of the sockets 18.

The locking element 13 is provided, on one side thereof, with a plurality of locking teeth 19, preferably formed integral with said element, which, when said element is thrust inwardly—as shown in Fig. 2—project into the opening 10 of the casing through a suitable port 20 providing communication between the well 12 and said 85 opening. The locking element 13 is provided eccentrically with a key lock 21, preferably of the cylinder type. The rotatable barrel of this lock carries a locking lug 22 at its inner end, designed to cooperate with a locking groove 23 formed in the inner wall of the casing adjacent the base of the wall 12. Thus the locking element, when thrust inwardly and the lock 21 operated to cause the locking lug 22 to engage within the locking groove 23, is locked in locking position with its teeth 19 projecting into the opening 10, as shown more clearly in Fig. 2. To release the locking element the lock is operated to release the lug from the groove, 95 whereupon the springs 17 force said element outwardly, as shown in Fig. 3, in which position the teeth 19 are removed from the opening 10.

A locking band or armored cable 24 is 100

used in conjunction with the lock, said band comprising a center cable or cables of heavy gauge wire, or the like, 25, on which are strung a plurality of link members 26, alternate ones of which are provided with semi-spherical projections 27 at opposite ends thereof, and the remaining links being provided with corresponding recesses 28 in their opposite ends, so that said links when the band is assembled, as shown in Figs. 1, 6, and 7, for instance, interfit so as to obstruct access to the wires 25 while at the same time rendering the band flexible, so that it may be passed around the article to be locked in substantially circular fashion, and drawn into firm clamping engagement therewith.

In Fig. 6 one method of clamping the center wires to the end links of the band is illustrated. In this figure the end link comprises a longitudinally socketed member 29, provided with diametrically opposite slots 30. An aperture 31 is provided in the inner end of the member 29, through which the wire cable or cables 32 extend into the socket provided in said member. At the point of entrance of the cables into the socket the former are bent laterally, as shown, and a plug 33 is then secured firmly in the socket with its lower end bearing down upon the laterally extending portions of said cables to clamp the same firmly against displacement. The free ends of the cables are then bent upwardly against the sides of the plug, so as to lie within the slots 30. A thimble or sleeve 34 is then moved into the position shown, so as to cover the slots, hold the free ends of the cable firmly against the plug 33, and prevent access thereto. The plug, preferably, has a screw-threaded engagement with the socket, and is positioned by means of any suitable tool which is engaged within the slot 35 at the outer end thereof, said plug being of such length that said outer slotted end projects beyond the end of the link member after said plug has been finally positioned, as shown in dotted lines in Fig. 6. This end of the plug is then ground off flush with the corresponding end of the link, so as to prevent removal thereof.

One end link of the band is slightly enlarged at its outer end to provide, in effect, a head 36, while the other end link is straight from end to end, or substantially of the same diameter throughout. In positioning the band in the lock the straight end thereof is inserted through the opening 11 of the casing 9, and drawn therethrough until the head 36 of the link at the opposite end of the band engages the countersunk shoulder 37 at one end of said opening. This engagement between the head and the shoulder prevents the band from being pulled all the way through the opening. The cable is then passed around the article to be locked and the free end thereof then

inserted through the opening 10 of the casing, the locking element having been previously released so that the teeth thereof are removed from said opening. The free end of the cable is then pulled so as to bring the same into firm clamping engagement with the article to be locked, after which the locking element 13 is thrust inwardly, whereupon the teeth 19 thereof are projected into the opening 10 and into locking engagement with said cable. In this position the locking element is locked, and serves effectively to prevent removal of the cable, as will be readily appreciated.

In Fig. 7 a slightly modified form of locking band is illustrated. In this construction the links are strung upon a single strand of wire and the links at the opposite ends thereof are provided with screw-threaded sockets 38, the ends of the wire entering said links through the inner ends thereof being cut off and bent laterally, so as to lie against the bottom of said sockets. A small plug 39, having a groove 40 therein, is then driven into the socket and into firm engagement with the bent end of the wire, with the latter lying within said groove 40. A screw-threaded plug 41 is then screwed firmly down upon the plug 39, so as to hold the same firmly in position. The plug 41 is also preferably made longer than necessary and slotted in its outer end for convenience in positioning the same, said slotted end being afterwards ground off to prevent removal of the plug.

It will be obvious that the present improvements are susceptible of many changes and modifications without departing from the spirit of the invention, and accordingly it is not desired to limit or restrict the same, except where limitations appear in the appended claims.

I claim:—

1. In a lock, a casing having a plurality of openings extending therethrough and a well formed therein, an element slidably mounted in said well and provided with a locking tooth designed to project into one of said openings in one position of said element, means for locking said element in such position, said locking means being housed within said element, and means for automatically moving said element to disengage said tooth upon release of said locking means.

2. In a lock, a casing having a plurality of openings extending therethrough and a well formed therein, an element slidably mounted in said well and provided with a locking tooth designed to project into one of said openings in one position of said element, means for locking said element in such position, said locking means being housed within said element, means for automatically moving said element to disengage said tooth

upon release of said locking means, and means for guiding said element in its movement and for limiting the latter upon such release.

- 5 3. The combination with a locking member of a locking band associated therewith and designed to encompass the article to be locked, said band comprising a cable, a plurality of links strung thereon and interfitting so as to obstruct access to said cable, the end link of said band being provided with a socket having a slot in the wall thereof, said cable entering said socket through an aperture in the base thereof and being then bent laterally and upwardly so as to lie within
- 10 said slot, a thimble engaging over said link and covering said slot from the exterior, and a plug fitting said socket and engaging said
- 15

cable at the bottom thereof and overlying said slot on the interior.

4. The combination with a locking member of a locking band associated therewith and designed to encompass the article to be locked, said band comprising a cable, a plurality of links strung thereon and interfitting so as to obstruct access to said cable, the end link of said band being provided with a socket, said cable entering the latter through an aperture in the base thereof and being then bent laterally, and a plug fitting said socket and bearing down upon the bent end of said cable to lock the same against displacement.

In testimony whereof, I have subscribed my name.

THOMAS C. COOPER.
